FIGURE 1 is a top perspective view taken from the front of a combined aerosol cap, actuating button, and dispenser embodying my new design;

FIGURE 2 is a front elevational view thereof;

FIGURE 3 is a rear elevational view thereof;

FIGURE 4 is a top plan view thereof;

FIGURE 5 is a vertical sectional view of the cap thereof taken on line 5-5 of FIGURE 4;

FIGURE 6 is an enlarged side elevational view of the actuating button thereof; and

FIGURE 7 is a vertical sectional view of the actuating button thereof on the same scale as FIGURE 6.

The dominant features of my design reside in the full-line portions of the drawing.

I claim:

The ornamental design for a combined aerosol cap, actuating button, and dispenser, as shown and described.
